DEVICE FOR FASTENING SHEETS

Louis W. Karlen, Des Moines, Iowa

Application March 25, 1935, Serial No. 12,886

3 Claims. (Cl. 129—25)

This invention relates to sheet fasteners and more particularly to fasteners that are usually permanently attached to a backing sheet.

The principal object of my invention is to provide a two-piece sheet fastener that may be easily and quickly assembled for use.

A further object of this invention is to provide a two-piece sheet fastener that when once assembled for use will be yieldingly held against accidental detachment.

A still further object of my invention is to provide a detachable two-piece sheet fastener that successfully holds the sheet engaging and retaining arms against undesirable movement during the placing or removing of the sheets.

A still further object of this invention is to provide a sheet fastener that permits the selection of various length attachable sheet holding arms.

20 A still further object of my invention is to provide a sheet fastener of two parts that is of exceptionally thin construction and one that will not undesirably engage other folders in a filing cabinet when the folder to which it is secured 25 is being removed from or placed in the filing cabinet.

A still further object of my invention is to provide a sheet fastener of two parts that is economical in manufacture and durable in use.

30 These and other objects will be apparent to those skilled in the art.

My invention consists in the construction, arrangement, and combination of the various parts of the device, whereby the objects contemplated 35 are attained as hereinafter more fully set forth, pointed out in my claims, and illustrated in the accompanying drawing, in which:

Fig. 1 is a top plan view of my fastener secured to a backing sheet.

40 Fig. 2 is a back view of my fastener and more fully illustrating its construction.

I will now describe in detail the preferred form of construction of my two-piece sheet fastener. Obviously, many other forms can be used to accomplish the desired results. The one shown, however, will illustrate how the many troubles experienced heretofore in sheet fasteners have been eliminated.

45 In the drawing, I have used the numeral 10 to designate an ordinary backing sheet to which my fastener may be attached. I have used the numeral 11 to designate the flat base portion of the fastener. This base 11 has four pointed ear portions 12 integrally formed at the four corner ends respectively of the base. These ears 12

always extend transversely of the longitudinal axis of the sheets being held, as shown in Fig. 1. To secure this base 11 to a backing sheet 10 it is merely necessary to place the base 11 at the back of the backing sheet 10 and force the pointed ears 12 through the sheet after which the ears are clinched inwardly, as shown in the drawing. In most instances, openings are provided in the backing sheet to accommodate the pointed ears. By the ears 12 extending transversely of the backing sheet and sheets being held, the complete folder may be placed in or removed from a filing cabinet without danger of snaring another folder. This is possible, as the base member when so constructed, has no sharp corners, hooks, or free 15 marginal edges that might undesirably engage another folder.

The numeral 14 designates the usual bendable bar for piercing and holding sheet members to the back sheet 10. The numeral 16 designates 20 a bridge cut in the central portion of the base 11 and raised upwardly to provide an arch. When my fastener is assembled, this arch 16 extends upwardly through the backing sheet 10 as shown in Fig. 1 for receiving the bar 14. In 25 order that this bridge or arch portion will operate successfully it is necessary that it be of specific design. A study of the drawing will show that I have made this bridge 16 comparatively narrow at its center in order that there will be a substantial amount of the flat base member 11 back 30 of the central portion of the bar 14, as shown in Fig. 2. This construction permits a very small opening from which the bridge 16 is cut and there is no danger of the bar 14 bending on one center 35 line and tending to pass through the opening under the bridge 16 when the two outer ends of the bar 14 are bent upwardly to receive the sheet members. The numeral 15 designates two downwardly extending projections on the bar 14. 40 These projections 15 snap into the opening under the bridge 16 when the bar 14 is slid into proper position under the bridge 16.

Some changes may be made in the construction and arrangement of my improved device for 45 fastening sheets without departing from the real spirit and purpose of my invention, and it is my intention to cover by my claims any modified forms of structure or use of mechanical equivalents which may be reasonably included within 50 their scope.

I claim:

1. In a sheet fastener, a substantially flat one piece base member having an arch cut from its area and extending above its general top surface; 55

said arch and the opening in the base member from which it is formed having a decreased width near the center of their lengths, a plurality of bendable ears on said base member for securing 5 said base member to a backing sheet, and a manually bendable bar member mounted on said base member by extending below said arch.

2. In a sheet fastener, a base member having an arch cut from its area and extending above 10 its general top surface, a means for securing said base member to a sheet, a manually bendable bar member mounted on said base member by extending below said arch, and a projection on said

bendable bar member below said arch and engaging the opening in said base member from which said arch is formed.

3. In a sheet fastener, a base member having an arch cut from its area and extending above 5 the surface of that portion of the base member adjacent the portion from which said arch is cut; said arch and the opening in the base member from which it is formed having a decreased width near the center of their lengths, and a manually 10 bendable bar member detachably extending below said arch.

LOUIS W. KARLEN.
